UNITED STATES PATENT OFFICE.

HUGO SALOMO, OF MELBOURNE, ASSIGNOR OF ONE-HALF TO JOHN DRYSDALE AND JOHN FRASER, BOTH OF 131 KING STREET, WEST MELBOURNE, VICTORIA.

ROTARY PUMP AND BLOWER.

SPECIFICATION forming part of Letters Patent No. 351,129, dated October 19, 1836.

Application filed September 15, 1885. Serial No. 177,169. (No model.)

To all whom it may concern:

Be it known that I, HUGO SALOMO, a subject of the Emperor of Germany, residing at No. 148 Bourke Street west, in the city of Melbourne and British colony of Victoria, engineer, have invented an Improved Rotary Pump and Blower, of which the following is a specification.

This invention has been designed, principally, for use as a rotary pump, although it may also be used as a rotary blower. I intend to call it the "Hydraulant."

It consists of a novel combination of novel contrivances. These novel contrivances consist, first, of two pumping-disks; second, of two cheeks or casings to receive the pumping-disks, and, third, of a wedge-piece through which the supply enters. The pumping-disks are each made with a conical face and a recessed back. On the face of each are radial ribs or teeth extending from the center to the periphery, the faces of which ribs are wholly on the one plane. They each have a stop behind each rib, and they are each carried by their own spindle. The two cheeks or casings are dished to receive the pumping-disks, and are so made as that their lips or flanges meet for about one-half of their circumference and then diverge from one another, so as to leave a wedge-shaped space between them. On the outer side of each cheek is a projecting hollow boss, which forms a bearing for the spindle of the respective disks, and on the inner side, just beyond the periphery of the disks, are two suction-chambers. These cheeks are also so constructed as to provide a suitable discharge-opening. The wedge-shaped piece is made to accurately fit the wedge-shaped space left between the two halves of the two cheeks. The supply-pipe is made in it, and leads to a quadrant-shaped opening cut quite through it between the two disks, so as to allow the supply to pass from such opening to the spaces between the ribs or teeth of the disks on both sides of it.

In order, however, that this invention may be more clearly understood, reference will now

be made to the drawings hereto attached, in which—

Figure 1 is a plan looking down from the top, and Fig. 2 an end elevation, of this rotary pump and blower. Fig. 3 is a horizontal section on the center line *a a*, Fig. 2, but showing the disks by a top view in the act of working together. Fig. 4 is a side elevation of the machine with one of the disks and its casing taken off, and with part of the wedge shaped piece between the disks broken away in order to show the central section of the inlet-bend. Fig. 5 shows a face view of one disk *6c* within its casing. Fig. 6 is a horizontal section through the center of one of the disks affixed on its spindle.

In these figures, *A A* are the conical disks, made, preferably, of brass, and *A' A'* are the radial ribs or teeth projecting from their faces, one side of such ribs or teeth *c* being shaped similar to the teeth of a bevel-wheel, so as to allow them to gear with and work quite close to each other, as shown in Fig. 3. These disks are keyed upon their respective spindles *A²*, one of which is long enough to allow of the fly-wheel *A³* and pulley *A⁴* being secured thereon, so as to enable it to be driven either by manual power or by belt from any other moving machinery. The face and the ends or periphery of these ribs or teeth *A'* and the back wearing-edge of the conical disks are truly turned and work within their side cheeks, *B*, which have outwardly-projecting sleeves or bearings *B'*, to support the spindles *A²*. These cheeks are secured to the wedge-shaped piece *C* by the bolts *B²*, and to each other by the bolts *B³*, suitable flanges, *B³*, being provided upon them for that purpose.

By reference to Fig. 5 it will be noticed that each of the cheeks *B* has one-half of the outlet branch *B⁶* and a vacuum-recess, *B⁷*, formed in them, as shown. The wedge-shaped piece *C* is faced true upon its surfaces to allow of the disks on either side working against it, and in the upper portion of it is a quadrant-shaped opening, *C'*, quite through it, into which the inlet or suction branch *C²* leads. The lower

portion of said wedge-shaped piece beneath the chamber C' is hollow, and forms flanges to receive the bolts B², which flanges are cast or formed upon the lower or standard part, C⁴, of the wedge-shaped piece.

5 C⁵ is a foot-plate, in which are the holes C⁶, to receive the holding-down bolts for affixing the machine to its frame or foundation.

10 A⁵ are small projecting snugs upon the face of each conical disk near its outer edge, between which snugs and the ribs or teeth of the one disk the ribs or teeth on the opposite disk gear, and so prevent their striking against one another when the machine is reversed.

15 The arrows D show the course of the air or liquid passing through the machine.

The mode of operation is as follows: The inlet branch C² is connected to the suction-pipe. One of the disks is driven by machinery, or 20 otherwise, and those ribs or teeth which are beyond the point of the wedge-shaped piece C gear with those on the opposite disk, and so a rotary motion is imparted to it also. This 25 rotary motion produces a vacuum in the chamber C', into which the air or liquid finds ingress, and from whence it passes through the quadrant-shaped opening C³ into the spaces between the radial ribs or teeth A', which confine and carry it down between them and the 30 lower faces of the wedge-shaped piece C. Immediately it passes the point of this wedge-shaped piece the ribs or teeth A' begin and gradually increase the depth of their gear with each other, thereby ejecting the whole of the 35 air or liquid into the outlet or delivery branch B⁶. It will be observed that as the conical disks A are recessed at their backs the air or liquid finds entrance thereto, and so forms a cushion, which materially assists in causing the 40 said disks to rotate freely on their working-faces by preventing any undue friction.

Having now particularly described and explained the nature of my said invention and in what manner the same is to be performed, 45 I declare that what I claim is—

1. The herein-described rotary pump, comprising the two-part casing B, each part having one-half of the outlet branch and of an air-chamber, B⁷, formed therewith, and constructed to form a wedge-shaped space between them when assembled, the wedge-shaped piece C, having inlet branch C² and sector-shaped inlet-ports C³ formed therewith, and conical winged or ribbed disks arranged to rotate on opposite sides of the wedge-shaped piece C, 55 substantially as described, for the purpose specified.

2. The combination, substantially as herein described, of the two-part casing B, provided with tubular shaft-bearings and interior recesses, B⁷, said parts being constructed to form a wedge-shaped space between them when assembled, the wedge-shaped piece C, having inlet branch formed thereon, and provided with sector-shaped inlet-ports C³, arranged in 60 said wedge-shaped space and dividing a portion of the interior of the casing into two chambers of like cross-sectional area, with the conical winged or ribbed disks A', having one side or face, c, constructed in the form of a bevel gear-tooth and arranged to rotate on opposite sides of the wedge-shaped piece C, for the purpose specified.

3. The combination of the two-part casing B, having outlet branch B⁶ and interior recesses, B⁷, and the wedge-shaped piece C, having inlet-branch C², chamber or passage C', and sector-shaped inlet-ports C³, with the conical revoluble disks A, having ribs or wings A', the face c of which has the form of a beveled gear-tooth, and provided with projecting snugs A⁵, said disks being arranged to rotate on opposite sides of the wedge-shaped piece C, said parts being constructed, arranged, and operating substantially as described, for the purpose specified.

HUGO SALOMO.
